(57) **CLAIM**

The ornamental design for a combined dental pick and sheath, substantially as shown and described.

DESCRIPTION

FIG. 1 is a perspective view for my new design for a combined dental pick and its sheath;

FIG. 2 is a right side elevational view of the sheath portion, which is shown separately for clarity of illustration;

FIG. 3 is a right side elevational view of the dental pick, which is shown separately for clarity of illustration. Left side is a mirror image;

FIG. 4 is a top plan view, the bottom view is a mirror image thereof;

FIG. 5 is a top plan view of the sheath, the bottom view is identical;

FIG. 6 is a top end elevational view of the sheath;

FIG. 7 is a bottom end elevational view of the dental pick;

FIG. 8 is a bottom end elevational view of the sheath; and,

FIG. 9 is an exploded perspective view of the combined dental pick and sheath.
